UNITED STATES PATENT OFFICE.

PATRICK MEEHAN, OF LOWELLVILLE, OHIO.

GAS-WASHER.

SPECIFICATION forming part of Letters Patent No. 784,748, dated March 14, 1905.

Application filed April 25, 1904. Serial No. 204,782.

To all whom it may concern:

Be it known that I, PATRICK MEEHAN, a resident of Lowellville, in the county of Mahoning and State of Ohio, have invented a new and useful Improvement in Gas-Washers; and I do hereby declare the following to be a full, clear, and exact description thereof.

My invention relates to gas washers or scrubbers; and its object is to provide a device of this kind which is simple of construction, not liable to get out of order or repair, easy to clean, and which will thoroughly remove the impurities from the gas and afterward dry the same.

15 In the accompanying drawings, Figure 1 is a side elevation of my improved washer. Fig. 2 is a vertical section therethrough. Fig. 3 is an end elevation thereof. Figs. 4, 5, and 6 are horizontal sections taken, respectively, on the lines 4 4, 5 5, and 6 6 on Fig. 2. Fig. 7 is a vertical section taken on the line 7 7, Fig. 2. Fig. 8 is a detail of the spray-pipe, and Fig. 9 is a detail of one of the spiral plates.

25 My gas-washer is constructed entirely of plate or similar metal, no brickwork or the like being used. The construction is such that the dirt can find no lodgment, but will be washed down and deposited in the base, which is so constructed that it can be readily cleaned 30 without interfering with the continuous operation of the washer.

The washer comprises two vertically-arranged chambers 1 and 2, which preferably are cylindrical in cross-section, although this 35 shape is not essential. These chambers are connected at their bottoms by a horizontal chamber 3, the lower portion of which is substantially trough-shaped. The gas-inlet is through a port 4 at the top of the chamber 1 and the gas-outlet through a port 5 at the top of the chamber 2. The course of the gas is downwardly through the chamber 1, across 40 through the chamber 3, and upwardly through the chamber 2.

45 Extending downwardly through the center of the chamber 1 is a perforated spray-pipe 7, having a connection at its upper end to a supply-pipe 8 and being provided with a regulating or cut-off valve 9 in this connection.

50 The openings 10 in this spray-pipe prefer-

ably slope downwardly, as shown in Fig. 8, so that the sprays of water will be given a downward direction. The perforations are arranged all around the pipe, so as to spray the water in all directions, and sufficiently close 55 together to insure the spraying of all the gas.

Arranged in the chamber 1 are a series of funnel or basin shaped baffle-plates 12, alternating with a series of cone-shaped baffle-plates 13. The basin-shaped baffle-plates 60 have their outer edges secured to the walls of the chamber 1, and said plates project downwardly and inwardly toward the center of the chamber, thus forming annular downwardly-sloping walls. The cone-shaped baffle-plates 65 13 are placed with their apices upwardly and substantially at the center of the chamber with their walls projecting downwardly and outwardly. These cone-shaped plates are supported from the walls of the chamber by 70 suitable arms or brackets 15. The spray-pipe 7 extends downwardly substantially through the centers of the openings in the baffle-plates 75 12 and through the apices of the plates 13.

When the gas enters the chamber 1, it expands somewhat in the enlarged upper portion thereof, thus causing it to lose its velocity and permitting the heavier impurities to fall. The gas is then again contracted to pass through the first basin-shaped plate 12, below 80 which it again expands, thus depositing more of the dirt. It is then again contracted to pass around the outer edge of the first cone-shaped baffle-plate 13, again expands underneath the same, is again contracted by the 85 next basin-shaped plate, again expands underneath the same, and so on continuously until it leaves the bottom of the chamber 1. In its course downwardly through this chamber, therefore, the gas is subjected to a series of 90 expansions and contractions, thus causing the same to separate repeatedly and insuring the depositing or falling down of practically all of the impurities in the gas. As no part of the interior surfaces of the chamber are free 95 from water, the impurities will be thoroughly saturated as soon as they drop, and thus prevented from again rising. The spray from the pipe 7 not only permeates the gas, but falls upon the sloping surfaces of the various baf-

100

ble-plates, from which it falls down in thin sheets to the plate next below. The course of the gas is such that it must pass through these sheets of water, and in that way it becomes 5 thoroughly washed.

As many baffle-plates will be arranged in the vertical chamber as will be found necessary. In the drawings three basin-shaped plates and two cone-shaped plates are shown; but this 10 number obviously can be varied as necessary or desired.

The gas may be quite hot when it first enters the chamber 1. To prevent overheating the head of the chamber, I place an inner 15 plate 17 underneath the head and in quite close proximity thereto. The plate will be supported by suitable brackets; so that its edges will not touch the walls of the chamber. Several of the openings 10 of the spray-pipe will 20 be above this inner plate 17, so that a thin sheet of water will constantly flow over said plate and drop down around the edges thereof, thus keeping said plate and the head of the chamber cool.

25 In the horizontal chamber 3 are arranged a series of vertical scrubber-plates 20, which extend longitudinally of said chamber and between which the gas must pass in its course from the chamber 1 to the chamber 2. Extending 30 transversely across the top of these scrubber-plates are a number of spray-pipes 21, three such pipes being shown, although the number may be varied. These pipes are provided with openings extending downwardly and in opposite directions, so as to direct sprays between the plates 20, as shown in Figs. 2 and 6. This keeps the surfaces of the scrubber-plates thoroughly moistened, and as they are set quite close together the gas 35 will come in contact therewith and have removed from it any impurities which may have escaped the washing process in the vertical chamber 1.

The horizontal pipes 21 receive their supply 45 of water, some from the vertical pipe 7 in the chamber 1 and others from a pipe 23, extending centrally through the chamber 2 and connected at its upper end to the supply-pipe 8 and having in the connection a controlling- 50 valve 24. Suitable regulating-valves will also be supplied in the connections with the horizontal pipes 21.

In the lower portion of the chamber 2 are arranged a series of baffle-plates 26, which 55 extend radially from the center to the outer walls thereof, as shown in Fig. 5. These plates have a spiral trend, as indicated in Figs. 2 and 9, so as to give a spiral motion to the gas and separate it. Three such series of 60 plates are shown arranged vertically over each other, although only one or even more than three series might be employed, if necessary. These plates have their outer edges provided with flanges 27 for riveting to the walls of 65 the chamber 2. The upper edges of the top

series of plates are curved over to one side, as shown at 28; while along said edges on the opposite side is riveted a similar curved plate 29, thus forming downwardly-directed troughs or gutters along the upper edges of these plates. These curved edges are shown only on the upper series of plates; but in practice all of the series of plates may and preferably will be supplied with such curved edges. The baffle-plates 26 may be used either as scrubbers or driers, according to circumstances or the character of gas being washed. When used as scrubbers, the lower portion of the pipe 23 will be perforated, as shown in Fig. 2, so that sprays of water will be directed against these baffle-plates and will flow or drip down the same, and as the gas is given a spiral trend between the plates, practically all portions thereof will come in contact with these plates. In this way any impurities which 8 may still remain in the gas will be removed. The curved upper edges of the plates will arrest any water that might flow upwardly with the gas. For most gases, however, the scrubbers in the vertical chamber 1 and horizontal 9 chamber 3 will suffice to remove all the impurities; and in that case the vertical pipe 23 will not be perforated or at least will not be supplied with water. The baffle-plates 26 then act as drying-plates to condense the 9 moisture carried forward with the gas, the curved upper edges of the plates arresting any water that might flow upwardly with the gas. Above these spiral baffle-plates is arranged a drier, which consists of two heads 30, extending transversely across the chamber and having extending therethrough a series of tubes 31, through which the gas must flow. These tubes of themselves will act to condense any moisture that may be in the gas; but when by reason of the great impurities of the gas the baffle-plates 26 are used as scrubbers rather than driers it is preferred to heat the tubes 31, so as to more efficiently dry the gas. This is accomplished by circulating steam 11 around the tubes 31 between the heads 30, as can be conveniently done by providing a steam-inlet 32 and a steam-outlet 33 for the space between the heads 30. In addition to this drier a steam or other heated jacket 35 11 may be provided in the outlet-pipe from the port 5.

All of the scrubbing and drying surfaces are of metal and have smooth surfaces which slope downwardly, and there is no place on which 12 dirt or anything else can lodge. The dirt is washed down into the chamber 3 and deposited, together with the water, in the lower portion thereof. The water-level in the chamber is maintained by providing in the wall at one 12 end an opening 36, which leads to a projecting portion 37, provided with an overflow-pipe 38; whereby the level of the water is always maintained at substantially the same level. The opening 36 is adapted to be entirely or 13

partially closed by a vertically-movable gate 40, which may be raised and lowered in any suitable manner, as by means of cords or chains 41, secured to suitable winding-drums 42 on a shaft 43, which in turn is controlled

5 from a hand-wheel 44, having connected thereto a suitable drum connected by a chain or cord 45 with a similar drum on the shaft 43. The gate 40 will be set at such a height as

10 to maintain a seal at the opening 36 and prevent the escape of gas. Through the opposite end of the chamber 3 project a series of nozzles 48, three such nozzles being shown; but obviously a larger number might be em- 15

ployed. These nozzles are connected to any suitable source of water-supply and supply jets of water practically horizontally in the chamber 3. These jets are applied at the surface of the water in said chamber and are di- 20

rected toward the opening 36 at the opposite end. As a consequence any light dirt or impurities that float on top of the water will be blown toward the opening 36 and out through the same to the overflow-pipe 38. This keeps 25

the surface of the water clean, so that any impurities that drop into the same will be imme- 30

diately saturated and prevented from again rising. Should froth or similar light matter ac- 35

cumulate on top of the water and not be able 40

to pass underneath the gate 40, the latter may 45

be slightly raised at intervals, so as to permit 50

such light matter to escape. The sprays from 55

the nozzles 48 also create a current which as- 60

sists the gas in its flow through the scrubber. 65

35 The heavier particles of impurities settle 70

down in the trough-like bottom of the cham- 75

ber 3. This bottom is provided with one or 80

more funnels or hoppers 50, closed by bell- 85

valves 51. The latter may be operated in any 90

95 suitable way, such as being supported on the

counterweighted levers 52, controlled from the rods 53, as will be readily understood. 100

These valves will be opened at intervals to permit of the flushing out of the apparatus. 105

45 When this is done, the gate 40 will be low- 110

ered to entirely close the opening 36 and seal the latter. Then the valves 51 will be opened, 115

permitting all of the water and dirt in the

base of the device to be washed out. The

120 sprays of water coming down through the vari- 125

ous spray-pipes will thoroughly flush out the

same, and this can be done without stopping 130

the flow of gas through the apparatus. If

necessary, a hose or scraper may be intro- 135

duced into the chamber to facilitate cleaning. 140

The overflow and dirt fall down into a suit- 145

able gutter or sewer, such as 55, and all of 150

the spray-pipes have connected to them down- 155

wardly-projecting flushing-pipes 56, provided

60 with suitable controlling-valves 57, so that

whenever necessary any dirt which may ac- 160

cumulate in the lower ends of these pipes may 165

be flushed out.

65 The washer described will be supported upon

a suitable base and will be provided with man-

holes, whereby access may be had to the in- 70

terior for cleaning or repairing. A ladder 60 is

provided to give access to the top of the ap- 75

paratus and to the manholes on the side of the

device.

75 The course of the gas through the apparatus will be understood from the foregoing de- 80

scription. In its course the gas is subjected

in the chamber 1 to alternate expansions and

contractions, is thoroughly sprayed with wa- 85

ter, and must pass through the several sheets

of water falling from one baffle-plate to the

next. In the horizontal chamber 3 it is sub- 90

jected to the further scrubbing action of the

plates 20 and jets coming from the spray- 95

pipes 21. Generally this suffices, and in the

upward course through the chamber 2 it will

be subjected to the drying action of the baffle- 100

plates 26 and tubes 31. Should, however,

the gas be very dirty, it may be subjected to 105

further washing while passing through the

spiral baffle-plates 26, and in that event it will

be dried by the heated tubes 31 and, if neces- 110

sary, further dried by the heated jacket 35.

All impurities in the water will be carried 115

down into the base of the chamber 3. The

light impurities will flow off through the

opening 36, while the heavier ones will set- 120

tle to the bottom, whence they can be period- 125

ically removed by opening the valves 51. The 130

water-level is automatically maintained and a

complete seal is provided by the door 40.

No brick or other similar material is used 135

in the washer; but the construction is entirely

metallic, and all surfaces are smooth and have 140

a downward slope, so that the dirt and water

can find lodgment only in the bottom.

145 There is practically nothing in the device

which can get out of repair or working or- 150

der, and the construction is such that any re- 155

pairs that become necessary can be readily

made and without stopping the apparatus.

When necessary, the spray-pipes can be taken

out and replaced, and they can be kept clean

by merely blowing the dirt out of them, as 160

can be done by opening the valves at their

lower ends. It is impossible for the spray- 165

pipes or other parts to become clogged with

dirt.

170 What I claim is—

1. In a gas-washer, the combination of a 175

chamber having a gas-inlet and a gas-outlet,

baffle-plates in said chambers so arranged as

to cause alternate contractions and expansions

of the gas, means for spraying water onto 180

said baffle-plates, a series of vertically-ar- 185

ranged scrubber-plates in the bottom of said

chamber, and means for spraying water onto 190

said scrubber-plates.

2. In a gas-washer, the combination of a ver- 195

tical chamber having a gas-inlet at the top

and a gas-outlet from the bottom, basin- 200

shaped and conical baffle-plates arranged al- 205

ternately and oppositely at the outer walls

and center of said chamber to cause alternate 210

scrubbing action of the gas.

215

expansions and contractions of the gas, means for spraying water onto said baffle-plates, a second chamber connected to the bottom of said vertical chamber, and a series of spirally-arranged baffle-plates in said second chamber.

3. In a gas-washer, the combination of a vertical chamber having a gas-inlet at the top and a gas-outlet from the bottom, baffle-plates arranged in said chamber, a perforated pipe arranged vertically in said chamber to spray water onto said baffle-plates, and a plate arranged underneath the head of said chamber and below an opening or openings in the spray-pipe, whereby the top of said chamber will be kept cool.

4. In a gas-washer, the combination of a vertical chamber having a gas-inlet at the top and a gas-outlet from the bottom, a series of baffle-plates in said chamber, means for spraying water onto said baffle-plates, a series of vertically-arranged scrubber-plates in the bottom of said chamber, and spray-pipes extending across said scrubber-plates.

5. In a gas-washer, the combination of a vertical chamber provided with a gas-inlet at the top, a series of baffle-plates projecting into said chamber, means for spraying water onto said baffle-plates, a horizontal chamber communicating at one end with the lower end of the vertical chamber and having a gas-outlet from its opposite end, vertically-arranged scrubber-plates extending longitudinally of said horizontal chamber, and spray-pipes extending across said scrubber-plates.

35 6. In a gas-washer, the combination of a vertical chamber having a gas-inlet at its upper end, basin-shaped and conical baffle-plates arranged alternately and oppositely at the walls and center of said chamber, a perforated pipe arranged vertically in the center of said chamber, a horizontal chamber communicating at one end with the lower end of said vertical chamber and having a gas-outlet from its opposite end, vertically-arranged scrubber-plates in said horizontal chamber and extending longitudinally thereof, and spray-pipes extending across said scrubber-plates.

7. In a gas-washer, the combination of two vertical chambers communicating with each other at their lower ends, a gas-inlet at the upper end of one of said chambers and a gas-outlet from the upper end of the other chamber, a series of baffle-plates in the inlet-chamber, means for spraying water onto said baffle-plates, and spirally-arranged baffle-plates in the outlet-chamber.

8. In a gas-washer, the combination of two vertical chambers communicating at their lower ends, a gas-inlet into the upper end of one of said chambers, and a gas-outlet from the upper end of the other chamber, a series of baffle-plates in the inlet-chamber arranged to cause alternate expansions and contractions of the gas passing therethrough, means for spraying water onto said baffle-plates, and

spirally-arranged baffle-plates in the outlet-chamber.

9. In a gas-washer, the combination of two vertical chambers communicating at their lower ends, a gas-inlet into the upper end of one of said chambers and a gas-outlet from the upper end of the other chamber, basin-shaped and conical baffle-plates arranged alternately and oppositely at the walls and center of the inlet-chamber, a perforated spray-pipe arranged vertically at the center of said chamber, and spirally-arranged baffle-plates in the outlet-chamber.

10. In a gas-washer, the combination of two vertical chambers, a gas-inlet into the top of one of said chambers and a gas-outlet from the top of the other chamber, a horizontally-arranged chamber connecting the lower ends of the two vertical chambers, baffle-plates in the inlet-chamber, means for spraying water onto said baffle-plates, vertically-arranged scrubber-plates in the horizontal chamber and extending longitudinally thereof, means for spraying water onto the same, and gas-drying means in the outlet-chamber.

11. In a gas-washer, the combination of two vertical chambers, a gas-inlet into the upper end of one of said chambers and a gas-outlet from the upper end of the other chamber, a horizontally-arranged chamber connecting the lower ends of said vertical chambers, basin-shaped and conical baffle-plates arranged alternately and oppositely at the walls and center of inlet-chamber, a perforated spray-pipe arranged vertically and centrally in said chamber, vertically-arranged scrubber-plates in the horizontal chamber and extending longitudinally thereof, spray-pipes extending across said scrubber-plates, and gas-drying means in the outlet-chamber.

12. In a gas-washer, the combination of a chamber provided with a gas-inlet, baffle-walls therein, means for spraying water onto the same, a second chamber communicating with said first-named chamber and provided with a gas-outlet, and heated drying means in said second chamber.

13. In a gas-washer, the combination of two vertical chambers communicating at their lower ends, a gas-inlet into the upper end of one of said chambers and a gas-outlet from the upper end of the other chamber, baffle-plates arranged in the inlet-chamber to cause alternate expansions and contractions of the gas, means for spraying water onto said baffle-plates, a series of drying-tubes in the outlet-chamber, and means for heating said tubes.

14. In a gas-washer, the combination of two vertical chambers communicating at their lower ends, a gas-inlet into the upper end of one of said chambers and a gas-outlet from the upper end of the other chamber, a series of baffle-plates in the inlet-chamber, means for spraying water onto said plates, a pair of heads or walls extending across the outlet-chamber,

tubes extending through said heads or walls, and a steam inlet and outlet for the space between said heads.

15. In a gas-washer, the combination of two vertical chambers communicating at their lower ends, a gas-inlet into the upper end of one of said chambers and a gas-outlet from the upper end of the other chamber, baffle-plates in the inlet-chamber, means for spraying water onto said baffle-plates, and a series of spirally-arranged baffle-plates in the outlet-chamber.

16. In a gas-washer, the combination of two vertical chambers communicating at their lower ends, a gas-inlet into the upper end of one of said chambers and a gas-outlet from the upper end of the other chamber, baffle-plates in the inlet-chamber, means for spraying water onto said baffle-plates, and a series of spirally-arranged baffle-plates in the outlet-chamber, 20 said baffle-plates having downwardly-projecting gutters at their upper edges.

17. In a gas-washer, the combination of a scrubbing-chamber, a chamber communicating therewith, a series of spirally-arranged plates therein, and heated drying means in said chamber above said spirally-arranged plates.

18. In a gas-washer, the combination of a scrubbing-chamber, a chamber communicating therewith, a series of spirally-arranged plates 30 in said second chamber and provided with downwardly-directed gutters at their upper edges, and heated drier-tubes arranged above said spiral plates.

19. In a gas-washer, the combination of a 35 scrubbing-chamber, a second chamber communicating therewith, heated drying-pipes therein, an outlet-pipe from said chamber, and a heated jacket in said pipe.

20. In a gas-washer, the combination of two 40 vertical chambers, a gas-inlet in the upper end of one of said chambers and a gas-outlet from the upper end of the other chamber, a horizontal chamber connecting the lower ends of said vertical chambers, baffle-plates in the inlet-chamber, means for spraying water onto 45 said plates, scrubber-plates arranged vertically and extending longitudinally in said horizontal chamber, means for spraying water on said scrubber-plates, and a series of spirally-arranged baffle-plates in the outlet-chamber.

21. In a gas-washer, the combination of two 50 vertical chambers, a gas-inlet into the upper end of one of said chambers and a gas-outlet from the upper end of the other chamber, a horizontal chamber connecting the lower ends of said vertical chambers, a series of baffle-plates in the inlet-chamber, means for spraying water onto said plates, a series of vertically-arranged plates in the horizontal chamber 55 and extending longitudinally thereof, means for spraying water onto said scrubber-plates, and a series of spirally-arranged baffle-plates in the outlet-chamber and provided at their upper edges with downwardly-directed 60 gutters.

22. In a gas-washer, the combination with two vertical chambers, a gas-inlet into the upper end of one of said chambers and a gas-outlet from the upper end of the other chamber, a horizontal chamber connecting the lower ends of said vertical chambers, baffle-plates in the inlet-chamber, means for spraying water onto said baffle-plates, vertical scrubber-plates in the horizontal chamber and extending longitudinally thereof, means for spraying water 70 onto said scrubber-plates, spirally-arranged baffle-plates in the outlet-chamber, and heated drier-tubes in said chamber above said spiral baffle-plates.

23. In a gas-washer, the combination of two 80 vertical chambers communicating at their lower ends, a gas-inlet into the upper end of one of said chambers and a gas-outlet from the upper end of the other chamber, baffle-plates arranged in both of said chambers, and 85 perforated pipes arranged vertically in both of said chambers.

24. In a gas-washer, the combination of two vertical chambers communicating at their lower ends, a gas-inlet into the upper end of 90 one of said chambers and a gas-outlet from the upper end of the other chamber, basin-shaped and conical baffle-plates arranged alternately and oppositely at the walls and center of the inlet-chamber, a perforated pipe 95 arranged vertically and horizontally in said chamber, spiral baffle-plates in the outlet-chamber, and a perforated pipe arranged vertically and centrally in said chamber.

25. In a gas-washer, the combination of two 100 vertical chambers communicating at their lower ends, a gas-inlet into the upper end of one chamber and a gas-outlet from the upper end of the other chamber, baffle-plates in the inlet-chamber, means for spraying water onto 105 said baffle-plates, spirally-arranged plates in the lower portion of the other chamber, a perforated pipe arranged vertically in said chamber, and heated drier-tubes in the upper portion of said chamber.

26. In a gas-washer, the combination of two 110 vertical chambers, a gas-inlet into the upper end of one chamber and a gas-outlet from the upper end of the other chamber, scrubbing means in the inlet-chamber, gas-drying means 115 in the outlet-chamber, a horizontal chamber connecting the lower ends of said vertical chambers and having an overflow-outlet at one end, and jets projecting through the opposite end of said chamber and applied at the surface 120 of the water and directed toward the overflow-opening.

27. In a gas-washer, the combination with two vertical chambers, a gas-inlet into the upper end of one chamber and a gas-outlet from 125 the upper end of the other chamber, scrubbing means in the inlet-chamber, gas-drying means in the outlet-chamber, a horizontal chamber connecting the lower ends of said vertical chambers and having an overflow-opening at 130

one end, a gate for controlling said opening, and jets projecting through the opposite end of the chamber and applied at the surface of the water and directed toward the overflow-opening.

28. In a gas-washer, the combination of a vertical scrubbing-chamber, a collecting-chamber at the bottom thereof provided with a trough or hopper bottom, cleaning-valves in

said bottom, an overflow-opening at one side of said chamber, and a seal for closing said opening.

In testimony whereof I, the said PATRICK MEEHAN, have hereunto set my hand.

PATRICK MEEHAN.
